US00D859225S

(12) **United States Design Patent** (10) **Patent No.:** **US D859,225 S**
(45) **Date of Patent:** **** Sep. 10, 2019**

(54) **WHEELED PERSONAL CONVEYANCE**

(71) Applicant: **Medline Industries, Inc.**, Northfield, IL (US)

(72) Inventors: **John Kutsch**, Harvard, IL (US); **Corbett Brown, Jr.**, Round Lake Park, IL (US); **Zhiliang Wang**, Zhongshan (CN)

(73) Assignee: **Medline Industries, Inc.**, Northfield, IL (US)

(**) Term: **15 Years**

(21) Appl. No.: **29/669,154**

(22) Filed: **Nov. 6, 2018**

Related U.S. Application Data

(63) Continuation of application No. 29/604,446, filed on May 17, 2017, now Pat. No. Des. 834,462, which is a continuation of application No. 29/513,376, filed on Dec. 30, 2014, now Pat. No. Des. 789,256.

(57) **CLAIM**

The ornamental design for a wheeled personal conveyance, as shown and described.

DESCRIPTION

FIG. 1 is a top perspective view showing a first embodiment of a wheeled personal conveyance in accordance with our new design;

FIG. 2 is a bottom perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof;

FIG. 8 is a bottom plan view thereof;

FIG. 9 is a top perspective view showing a second embodiment of a wheeled personal conveyance in accordance with our new design;

FIG. 10 is a bottom perspective view thereof;

FIG. 11 is a front elevational view thereof;

FIG. 12 is a rear elevational view thereof;

FIG. 13 is a right side elevational view thereof;

FIG. 14 is a left side elevational view thereof;

FIG. 15 is a top plan view thereof; and,

FIG. 16 is a bottom plan view thereof.

The broken lines are included for the purpose of illustrating unclaimed subject matter and form no part of the claimed design.

1 Claim, 16 Drawing Sheets
